(57) **CLAIM**

The ornamental design for a pneumatic shock wave therapy gun, as shown and described.

DESCRIPTION

FIG. 1 is a top, rear and right side perspective view of a pneumatic shock wave therapy gun, showing my new design;

FIG. 2 is a bottom, front and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 2;

FIG. 12 is an enlarged view of portion 12 in FIG. 2;

FIG. 13 is an enlarged view of portion 13 in FIG. 2; and,

FIG. 14 is an enlarged view of portion 14 in FIG. 7.

The evenly broken lines show the features of the pneumatic shock wave therapy gun that form no part of the claimed design. The unevenly broken lines define the boundaries of enlarged views and form no part of the claimed design.
